United States Patent Office

Des. 194,773
Patented Mar. 5, 1963

194,773

EMBOSSED SHEET MATERIAL OR SIMILAR ARTICLE

Ricardo J. Rivas, Cincinnati, Ohio, assignor to Gibson
Greeting Cards, Inc., Cincinnati, Ohio, a corporation of Ohio

Filed Feb. 15, 1961, Ser. No. 63,944

Term of patent 3½ years

(Cl. D92—1)

The FIGURE is a plan view of an embossed sheet material showing my new design. The design unit is contained between the dot and dash lines, which unit is repeated in successive relation as indicated by the extensions beyond the unit boundaries.

I claim:

The ornamental design for an embossed sheet material or similar article as shown and described.
